STANDING WAVE OSCILLATING SYSTEM

Ilia E. Mouromtseff and Harrell V. Noble, Wilkinsburg, Pa., assignors to Westinghouse Electric & Manufacturing Company, East Pittsburgh, Pa., a corporation of Pennsylvania

Application August 20, 1932, Serial No. 629,644

2 Claims. (Cl. 250—36)

Our invention relates to short-wave apparatus and particularly to apparatus for the generation and delivery of power at wave lengths of only a few meters.

5 It has been found that an efficient generator for frequencies of this order may be made by causing a vacuum tube to produce standing waves upon a pair of concentric tubular conductors. Our invention pertains to the efficient production and delivery of power by such a generator to any suitable load, such as an antenna, a furnace, or a therapeutic apparatus.

10 It is an object of our invention to provide a system in which the losses by radiation from the generator and similar losses from the connections between it and the load shall be minimized.

15 It is a further object of our invention to provide a coupling device which shall have a much greater fly-wheel action than coupling devices usually used heretofore ordinarily have and which shall also be capable of matching impedances.

20 It is a further object of our invention to employ a pair of concentric tubular conductors as a coupling device by producing standing waves thereon.

25 It is a further object of our invention to provide connections to the inner one of such a pair of conductors, through certain of which connections power may be received to maintain the standing waves and through others thereof power may be delivered. We have found that by properly spacing the connections, the ratio of potential received over one pair thereof to potential delivered over another pair may be controlled.

30 35 To any given impedance in the output circuit there corresponds an "equivalent impedance", which must be added vertically to the impedance actually present in the input circuit to give the impedance the input circuit has when coupled to the output circuit. We have found that the ratio of such equivalent impedance to the impedance in the other circuit is dependent only on the spacing of the connections.

40 45 It is a further object of our invention to provide a shield about a generator of standing waves whereby the loss of energy therefrom through radiation is minimized. We have found that by properly choosing the radius of such a shield, the phase of the waves reflected thereby may be controlled and the shield may thereby be made to possess a regenerative effect.

50 It is a further object of our invention to provide for an adjustment of the radius of the shield in order to control said phase.

55 It is another object of our invention to employ

impedance-matching devices in such way that the terminal impedance of the transmission line extending to the load shall produce a minimum of reflection. By this means we avoid the production of standing waves upon the transmission line, with the incidental losses resulting from high current density at certain points and from radiation.

5 It is a further object of our invention to so apportion the ratio of each impedance in the system to its corresponding equivalent impedance at the several coupling devices that the impedance presented to the oscillation generator is that for which it is most efficient.

10 Other objects of our invention, details of the structures employed, and the way in which such structures are associated into a system will be readily understood from the following description and accompanying drawing, in which

15 Figure 1 shows, partly by diagram and partly by sectional views, the system embodying the invention,

20 Fig. 2 is a top plan view of the generator and its shield, the sectional view of said generator and shield in Fig. 1 being upon the line I—I of Fig. 25 2, and

25 Fig. 3 is an enlarged view of a detail indicated by the line III—III of Fig. 2.

30 In Fig. 1 a vacuum tube, the lower portion of which is seen at 1, has its anode and grid connected respectively to an outer pipe 2 and an inner pipe 3, the connections being designed to produce minimum reflection, as disclosed in the patent of C. A. Boddie, No. 1,979,668, granted November 6, 1934, assigned to Westinghouse 35 Electric & Manufacturing Company.

35 Such a combination of a vacuum tube and concentric pipes constitutes an oscillation generator of high frequency producing standing waves upon the concentric pipes. The filament may be energized by a battery, a generator, or a transformer, the secondary of which has been shown on the drawing. Whatever the source of energy it is separated from the filament by choke coils. The center point of the transformer secondary or one 40 side of the energizing battery or generator is grounded and connected through an ammeter and a source of direct-current potential indicated at 45 5 to the outer one 2 of the pipes. The same point is also connected through another ammeter and a grid resistor 6 to the inner pipe 3.

50 A choke coil 7 in the first of these connections and a choke coil 8 in the other, ensure that the high frequency does not pass through these connections. The coils 7 and 8 are so located rela- 55

tive to each other that they are not electro-magnetically coupled. The connection 9 from the coil 8 through the outer pipe 2 to the inner pipe is made by providing a hole in the outer pipe which may or may not be occupied by an insulator as desired.

The connections 9 and 10 from the coils 7 and 8 are at as small a distance as possible from the neutral point of the pipes 2 and 3. That is, when the generator has produced standing waves upon the pipes, these connections are on opposite sides of and comparatively near to a potential node. The direct-current connections are, for this reason, without substantial influence upon the distribution of the high frequency potentials.

It is desirable to build the two-pipe structure so that it shall have a great flywheel effect; that is, so that the amount of energy which can be stored therein, changing from current to electrostatic charge and back to current each half-cycle, shall be large. Theoretical considerations show that the greatest flywheel effect can be obtained if the pipes 2 and 3 are of equal radii but this is, of course, physically impossible. Instead of attempting to approximate it we have chosen the radii of the pipes to accord with those radii of plate and grid in the vacuum-tube design which seem best adapted to this purpose. In the chosen form, the outer pipe 2 has an inner diameter equal to twice the outer diameter of the inner pipe 3.

The pipes 2 and 3 are mounted in any desirable way, for example, by means of insulators 11 connected to a mast 12. They are located at the center of a shield 13 which is made of sheet metal, wire mesh or other suitable material for reflecting electromagnetic waves of a wave length of a few meters. The shield may be grounded if desired.

The radius of the shield, which is approximately the same as the distance between the pipes and the shield, is approximately one-quarter of the wave length but provision is made for adjusting it. One method for providing adjustment is indicated at 14 and 15 by showing the shield as composed of two halves which overlap. The extent of overlap can be regulated by means of bolts 16 which have been illustrated in more detail in Fig. 3.

Insulators 17 and 18 are provided in the wall of the shield for accommodation of the connections 9 and 10 to the coils 7 and 8 which are preferably located inside of the shield.

Connections 21 and 22 extend from the inner pipe 2 through insulators 23 and 24 in the shield to a coupling device 25. The conductors 21 and 22 pass through the pipe 3 and holes are provided for their accommodation, which may, if desired, be equipped with insulators. The conductors 21 and 22 are symmetrically placed relative to the potential node upon the pipe and the distance from the node is greater than that separating the connections 9 and 10 from said node.

Instead of the conductors 21 and 22 being connected as shown, they may, if desired be both connected to the outer pipe 2 or one to one pipe and the other to the other pipe.

The coupling device 25 comprises an inner pipe 26 mounted upon a mast 27 by means of an insulator 28 and an outer pipe 30 mounted upon the same mast by means of insulators 31 and 32. In the illustration, the length of the pipes 26 and 30 is not shown. They are substantially the same length as the pipes 2 and 3, namely one-half of a wave length.

The conductors 21 and 22 extend through holes in the pipe 30 and are connected to the pipe 26 at points spaced away from the center thereof, which is a potential node. The pipe 26 is also connected to two conductors 35 and 36, which likewise extend through holes in the pipe 30. Insulators may, if desired, be supplied in the holes. The further from the potential node, the more necessary insulators will be. The connections 35 and 36 are symmetrical relative to the potential node and, in the embodiment chosen for illustration, are spaced closer to that node than the connections 21 and 22.

The conductors 35 and 36 extend to a second coupling device 40 mounted upon a mast 41 by means of one or more insulators 42. In the form chosen for illustration, the coupling device 40 has been shown as a helix which will function as an auto-transformer, but, if desired, the second coupling device may be a pair of concentric pipes 20 like the device 25. The output conductors 45 and 46 from the coupling device 40 extend to the load, which may be an antenna, a high-frequency furnace, a therapeutic device or any other apparatus to which frequencies corresponding to wave 25 lengths of only a few meters may be applied.

In the operation of the system, the vacuum tube 1 and the pipes 2 and 3 with their associated conductors produce standing waves, the energy for which is derived from the direct-current source 30. The frequency of the standing waves is determined by the length of the concentric pipes and will be such that the pipes are exactly one-half a wave-length long.

Although it is intended that substantially all 35 the energy departing from the pipes 2 and 3 should be conducted over the lines 21—22, some energy leaves the pipes by radiation. Such radiated energy is reflected from the shield 13 back onto the pipes 2 and 3. The radius of the shield is 40 approximately one-quarter of a wave-length. Radiations departing from the pipe 2 undergo a reversal of phase upon reflection from the shield 13 and pass a second time over a quarter wave distance before they again arrive at the pipe 3. 45 They are, therefore, approximately in phase with the waves upon the pipe 3 when these radiations arrive there.

If the vacuum tube generator produced no lag and the plate and the grid voltage were therefore maintained in strict phase-opposition, this would be the desirable phase for the reflected radiations, but there is usually a small lag between the plate voltage and exact opposition to the grid voltage. It is, therefore, desirable that 55 the reflected radiations arrive at the pipes with substantially the same degree of lag and, by slightly increasing the radius of the shield over the quarter wave-length, this relation can be obtained. This is done by adjusting the bolts 16 60 until the generator is operating most efficiently, which fact will be indicated by the readings of the meters in the plate and grid leads.

The conductors 21 and 22 deliver alternating current energy to the inner pipe 26 of the coupling 65 device 25. Standing waves are thus produced upon the device 25, a potential node being established at the middle of the pipes. The lines 35 and 36 are on opposite sides of this potential node. The distance along the pipe 26 from the node 70 determines what potential shall be impressed upon these lines. The ratio between the voltage delivered to the lines 35 and 36 and that received from the lines 21 and 22, is dependent upon the distance separating each pair of lines from the 75

potential node. In the structure, as illustrated, a smaller potential is delivered to the lines 35 and 36 than is received from lines 21 and 22, but this ratio may be reversed, if desired.

5 Lines 35 and 36 deliver potential to the coupling device 40 which may step up or step down the potential in the familiar way of an auto-transformer if a helix is used, or if a second coupling device of the form illustrated at 25 be used, 10 the change in potential will be effected in the way just described.

A vacuum tube generator of the kind here described is like other generators, in at least one respect, namely, that it will deliver power most 15 efficiently to one particular impedance. One of the considerations which govern the design of this apparatus is that best efficiency will be obtained when the impedance presented to the generator is of this amount.

20 The coupling devices herein described resemble an ordinary wound transformer in at least one respect, namely, that the impedance in the output circuit may be represented by an equivalent impedance in the output circuit. The ratio between 25 the actual impedance in the output circuit and the impedance which should be considered as added in the input circuit, in order to represent the effect of the impedance in the output circuit, we have called the impedance transformation 30 ratio, because of its close similarity to the similar ratio when ordinary transformers are used as coupling devices.

This ratio may be controlled in each coupling device by controlling the ratio between the spacing of the input connections and that of the output connections. An equivalent impedance must be added to the lines 21—22 to represent the effect of its being coupled to the lines 35—36 by the device 25. Because the connections of the conductors 21 and 22 to the pipe 26 are farther apart than the connections of the conductors 35 and 36 to that pipe, the equivalent impedance will be larger than the impedance in the line 35—36. On the other hand, if the distance separating conductors 21 and 22 along pipe 26 be smaller than the distance separating conductors 35 and 36 along that pipe, the equivalent impedance will be smaller than the impedance in the line 35—36.

50 The impedance of the line as the expression is used herein means the resultant of its own impedance and the load impedance whether the coupling be by an auto-transformer as shown or by another device like the device 25.

55 It is possible theoretically, by taking advantage of this property of the coupling device 25, to match the impedance of the load with the optimum impedance for the generator, by which is meant that the effective impedance at the generator, after the several impedance transformation ratios have been applied to the load impedance, can be made to equal the impedance for which the generator is most efficient.

Sometimes a single coupling device may not 65 accomplish this result without requiring conductors to be more closely spaced than is physically possible or voltages at certain points to be greater than convenient. Under these circumstances the use of several coupling devices in 70 tandem can be made to match impedances.

In the system, as illustrated, the vacuum tube 1 and its associated pipes 2 and 3 may be regarded as an oscillation generator of a type which produces standing waves; from which viewpoint the 75 illustrated system includes two coupling devices.

It is also possible to regard the vacuum tube as itself a generator of high frequencies and the pair of concentric pipes associated with it as a coupling device; from which viewpoint the illustrated system includes three coupling devices. In this latter aspect, the impedance to which the load impedance must be matched is that at which the vacuum tube itself most efficiently generates oscillations.

The plate and grid leads are connected to the 10 pipes 2 and 3 near to the potential node. Nevertheless, they are a certain distance apart. The leads 21 and 22 are placed at a distance apart which is selected in accordance with the voltage 15 it is desired to impress upon the conductors 21 and 22. The ratio between the distance separating these connections and the length of the system comprising pipes and tube determines not only the voltage delivered to the line but also the impedance upon the vacuum tube, regarded 20 as an oscillation generator, which will be equivalent to the impedance presented by the conductors 21 and 22.

If the line 21—22 is long, it would ordinarily be convenient for the line 35—36 to be short, 25 although the first line may be short and the other one long. With either arrangement, the long line, because it is carrying a high frequency, will have a pronounced tendency to produce standing waves, and in order to avoid this, the 30 terminal impedance of the line would have the value corresponding to what, in the theory of transmission lines, is called "perfect termination". This may be accomplished by selecting the proper impedance transformation ratio for 35 the coupling device at the delivery end of the line. Under these conditions, regardless of the impedance at the end of the line connected to the generator, reflections will be avoided and standing waves on the line will thus be im- 40 possible.

The correct terminal impedance for the line is dependent upon the "characteristic line impedance". The most effective transmission of energy over the line will thus be secured by so selecting 45 the impedance transformation ratio at the output end of the line that the impedance, looking from the line into the coupling device, has the proper relation to the characteristic line impedance. It is, therefore, possible by the use of two coupling 50 devices, one at each end of the line to obtain the necessary impedance transformation ratio between the load at the one end of the system and the generator at the other end of the system, select a convenient value for the characteristic line 55 impedance and still avoid standing waves on the line.

The connections from the coupling device 25 have been shown as extending to the inner pipe. It is possible to obtain coupling with all of the 60 connections going to the outer pipe only. It is also possible to obtain coupling with one pair of connections going to one pipe and the other pair to the other pipe, but of all these methods we have found that that in which all connections extend to the inner pipe is the more efficient.

Although we have illustrated an auto-transformer at 40, as an alternate form of coupling device, we find that usually better results are 70 obtained by using a single coupling device like that shown at 25, or, if two coupling devices are used, by making both of them of this form. This is partly because a coupling device of the form depending upon standing waves and comprising 75

two concentric pipes radiates less energy and thus loses a smaller percentage of power in the form of radiation than older forms and also because such a coupling device has a greater fly-wheel effect than an auto-transformer or a coupling device comprising a tuned circuit.

The greater fly-wheel effect also reduces the tendency to parasitic oscillations and thus economizes power. It also tends to eliminate the effects of any brief or rapid changes in the output of the generator, but if the changes in the output be slower, they will be faithfully reproduced in the final output from the system. For example, a modulation of standing waves of a few meters length by a frequency corresponding to an audible note is in no way interfered with by using a coupling device having a large fly-wheel effect.

Although we have specifically described and illustrated only one form of our invention, it will be obvious to those skilled in the art that many modifications thereof are possible. We, therefore, do not intend any limitation except such as is required by the prior art or indicated by the accompanying claims.

We claim as our invention:

1. A triode oscillator comprising an emissive cathode, a control electrode having a conducting cylinder connected thereto, a plate electrode having a second conducting cylinder coaxial with the first-named cylinder connected thereto, and a cylindrical conducting shield substantially coaxial with the first-named cylinder and having a diameter substantially equal to a half-wave length of the oscillations produced by said generator.

2. In combination a source of alternating current and a conductor attached thereto, said conductor having a length in proportion to the frequency of said alternating current whereby standing waves are produced thereon and a cylindrical reflecting shield concentric with and surrounding said conductor and having a diameter substantially equal to a half-wave length of said standing waves.

ILIA E. MOUROMTSEFF.
